WEAVING FRAME FOR HAND WEAVING

Margaret Louise Thackeray, Dereham, Norfolk,
EnglandApplication September 21, 1936, Serial No. 101,797
In Great Britain November 6, 1934

5 Claims. (Cl. 139—33)

This invention relates to weaving frames for use in connection with hand weaving apparatus and has for its object to provide a portable apparatus for hand or treadle weaving which can be readily erected and disassembled, which may be readily warped and mounted for weaving, and which can be equally readily adapted to serve for other purposes, for example as wool winding frame or embroidery frame.

10 According to this invention weaving apparatus comprises a hand weaving frame and a treadle weaving frame adapted for use upon said weaving frame, the said hand weaving frame and treadle weaving frame being each composed of 15 a number of readily disassembled bar elements, the hand weaving frame having a readily detachable heddle frame, and the treadle weaving frame being formed with an attaching device for readily adapting it to the hand weaving frame 20 in place of the said heddle frame, the treadle weaving frame having a plurality of heddles and treadles for individually actuating its heddles.

The weaving frame may be made of wood, metal or other suitable material and may consist of two 25 side pieces with two adjustable ends and legs to stand on the floor, or alternatively two shorter legs for use in bed, and may be fitted with cogged or other wheels for winding the bobbins. The whole of the parts is so constructed and fastened 30 together so as to be easily disassembled and packed in a small case.

A warper is provided which may consist of two triangular side frames with a removable cross piece and a rod or pins through the side pieces 35 on which the weaving frame may revolve. All these may be made of wood, metal or other suitable material. The warping frame may be used to support the weaving frame instead of the above mentioned legs during the weaving operation.

40 A treadle attachment that can be fitted to the weaving frame may be made of wood, metal or other suitable material, and consists of a rigid frame with carrier and reels or other contrivance for carrying the heddle cords to a number of foot 45 pedals. The whole of the parts are so constructed and fastened together as to be easily disassembled and packed in a small case.

In the accompanying drawings, Fig. 1 is a 50 perspective view of a weaving frame with a heddle lifter and comb mounted thereon; Fig. 2 is a perspective view of an extension device for use when producing long or shorter cloth lengths; Fig. 3 is a perspective view of a warping stand with weaving frame and comb in place; Fig. 4 is a 55 perspective view of a comb holder for use when

the top bar of the comb is removed; Fig. 5 is a perspective view of a suitable treadle attachment; Fig. 6 is a perspective view of a rocker attachment to facilitate pattern weaving; Fig. 7 is a perspective view of a suitable warp threader; Fig. 8 is a perspective view of an adjustable indicator for showing the order in which the treadles are to be used; Fig. 9 is a perspective view of a suitable bobbin winding device, and Fig. 10 is a perspective view of the warper embodied in the hand weaving apparatus.

Referring to the drawings the weaving frame shown in Fig. 1 comprises two parallel side bars 1, of square or other suitable section formed at both ends with co-axially extending threaded ends 2 and 3, front and rear respectively, passed adjustably through two transverse bars 2a and 3a about three inches wide and fitted with nuts 4 to enable the effective length of the frame to be adjusted. These side bars are provided with holes 5 through which can be passed pins 5a for connecting the bars 1 to a supporting frame 7. The side bars 1 support a heddle frame 6 provided with two angle section bars 6a slidable along the bars 1.

25 A driving pinion 8 can be rotatably supported near the top of one of the legs of the member 7 which supports one end of the bars 1. Mounted on a crank or handle fitted shaft 9, this pinion meshes with a smaller diameter one 10 on the 30 spindle of which is fitted a cup 11 adapted to receive one end of a bobbin 12 on which the weft to be inserted is wound. The other end of the bobbin is fitted in a cup-ended screw 13 rotatably supported by a bracket 14 fitted to the other 35 upright 7.

The heddle frame 6 adaptable to this apparatus has a pair of uprights 15 each having a slot at its upper end accommodating semi-circular plates 16 oscillatable on pins 17 passed through the 40 furcations of the slotted parts. A pair of parallel heddle rods 18a pass through apertures in the corners of these two semi-circular plates. These rods each carry a heddle (not shown) made of a continuous length of string with loops so arranged on the two rods that other loops may pass between alternate warp threads and allow either set of warp threads to be raised as the semi-circular plates are oscillated. A comb 24 is fitted across the bars 1 in front of the heddle.

45 The two transverse bars 2a and 3a serve initially to receive the warp and when it is required to wind the warp around them use may be made of the warping frame shown in Fig. 3. This frame comprises two side A frames 18 connected 50

50

55

together by a cross bar 19 detachably secured by wing nuts and bolts 20. Bracket plates 21 are fixed to the apices of the frames 18 and these carry inwardly directed co-axial studs 22 adapted 5 to engage in either pairs of apertures 5b or 5c in the side bars 1 of the weaving frame to obtain the correct balance of the frame according to whether the extension 1a is being used or not. Wing nuts 23 on these studs form abutments to retain the weaving frame on the warping frame and enable the weaving frame to be rotated between the side frames 18 which are of sufficient height to permit complete rotation of the weaving frame. During the warping operation the comb 24 with its top bar 24a removed is clamped between the cross bar 2a and the nuts 4 as illustrated in Fig. 3 whereby successive warp threads may be passed between successive teeth 24 as the weaving frame is rotated. During 10 the warping operation the heddle rods 18a are removed so that there will be no interference on the part of these rods with the proper positioning of the warp threads. After the warping operation is completed, the heddle rods are again positioned above the weaving frame and the warp threads are suitably supported from the heddle rods by means of a heddle, for the purpose of forming a shed, as hereinbefore explained.

The warping frame 18 may be used for supporting 30 the weaving frame during the weaving operation, as illustrated in Fig. 10, instead of the supporting frame 7 in Fig. 1, if desired.

The operation of weaving is as described in the specification of my prior British Patent No. 35 252,984.

A suitable treadle attachment with a number of individually actuated heddles is shown in Fig. 5. It is adapted to be mounted on the side bars 1. This attachment comprises a vertical oblong frame 26 with a pair of channel section blocks 27 fitted to the inner sides of the uprights, these blocks being adapted to be fitted over the bars 1 in place of the heddle frame base members 6a, for which purpose pins 27a are passed through such blocks and under the bars 1. The heddle rods 28 (only two of which are shown) correspond in number to the number of treadles 29, six of which are shown as an example. The heddle rods 28 are suspended from yokes 30, and the centre of each yoke receives the upper ends 50 of two cords 31 guided in opposite directions over a guide bar 32 bridging the upper horizontal member 26a of the frame 26 and a further frame bar 33 fixed to the upper ends of two uprights 55 34 fixed near their lower ends to the blocks 27. Each pair of cords 31 are brought together as at 31a and coupled by single cord 31b to the appropriate treadle 29. The cords 31 are guided over circular or semi-circular section guide bars 35, the upper ones of which are secured across 60 the frame bars 26a and 33.

The treadles 29 are guided between plates 36 secured vertically across the lower horizontal bar 26b and a further horizontal bar 26c of the frame 26 and they are additionally separated at their pivot ends by distance piece blocks 37 which in common with the treadles are threaded on to a pin 38 passed through a pair of upright bars 39 and secured by wing nuts 38a. The pin 70 38 can also serve to anchor the lower ends of two diagonal stay bars 40 secured at their upper ends by bolts and wing nuts 41 to the frame 26. Additional bracing bars 42 are connected across these stay bars 40 and the uprights 39

and are also detachably secured by bolts and wing nuts 43.

The treadles 29 are maintained in and returned to their normal positions by tension springs 44 connected to said treadles and to ligatures 44a anchored at their upper ends to a transverse bar 45 which in conjunction with a lower situated transverse bar 46 completes the frame appropriate to the support of the treadles. The bars 45 and 46 are detachably secured to the bars 39 by 10 bolts and wing nuts.

Adaptors such as shown in Fig. 2 may be provided to reduce or increase the size of the warp, such adaptors being in the form of a pair of bars 1a fitted at one end into a transverse flat bar 3b and threaded at their other ends for engagement in apertures 3c in the weaving frame bar 3a. Nuts 4a are threaded on to the threaded ends of these bars and the bars can as shown extend inside, or alternatively outside the said 20 weaving frame.

To facilitate manipulation of the heddle rods when pattern weaving without the treadle attachment a rocker device (see Fig. 6) is provided in the form of two uprights 47 carried by a 25 horizontal cross piece 48 and having rounded base parts 49 which rock on the side pieces of the weaving frame. When using the rocker device, the heddle rods 18a are taken out of their slots and laid across the frame together with 30 other auxiliary heddle rods in quantity according to the pattern being woven. The required sheds are then formed in succession by placing one or the other of these heddle rods in the rocker frame and rocking this by hand and there- 35 by raising the required warp threads.

The comb or reed 24 is slidable upon the bars 1 and has a removable top bar 24a the ends of which are apertured to align with bolt receiving apertures on the end corner pieces of the 40 comb or reed. Metal clips 50 such as shown in Fig. 4 can be used to secure the comb to the side pieces of the weaving frame and these clips can also be used for fixing the heddle frame. These clips are bifurcated plates the limbs of 45 which are of taper or wedge form. The lower edge of each clip is formed with a pair of lateral lugs 51 adapted to engage a side member 1 to hold the comb in position when the bifurcations 50a are pressed over the lower bar 24b of 50 the comb.

An indicator made of card, metal or wood is provided to indicate the order in which the treadles are to be used. A suitable form of such an indicator is shown in Fig. 8 and comprises 55 a casing in the form of two spaced parallel discs 52 formed integral with a pair of flat plates 53 abutted against each other and each bent L fashion at its lower end to provide a U shaped clamp 54 which can be engaged over a suitable 60 frame element of the apparatus for instance the member 24a. Disposed between the discs 52 is a rotatable disc formed with peripheral teeth 55 by which it can be rotated. This rotatable disc bears a succession of numerals indicating the order in which the treadles are to be used and adapted to be exposed through an aperture 56 in one of the discs 52.

A skein holder and bobbin winder suitable for use with the apparatus is shown in Fig. 9 and 70 comprises a base bar 57 which can be clamped by a bench or U shaped clamp 58 to a table or to the weaving frame. The base bar carries an upright four limbed support 59 for four spools 60 round which the skein 61 is shaped and fed. 75

The spools can be adjusted relatively to each other by fitting wing nuts 62 on pins 63 carrying them, these pins being adjustable in slots 64 in the upright. A bar 65 extends horizontally at right angles from the base bar and carries a slideable end bearing 66 for one end of the bobbin 67 onto which the wool is wound. The other end of the bobbin is fitted in a socket 68 formed with a spindle 69 rotating in a bearing bracket 70 at the free end of the said horizontally extending bar, this spindle carrying a small diameter friction wheel 71 or pulley driven by a larger diameter one 72, the spindle of which is mounted adjustably in said bearing bracket to enable the degree of friction to be adjusted. Alternatively gear wheels may be employed. The wound bobbin is employed as a shuttle for inserting the weft.

The warp threader (or leasing device) can as shown in Fig. 7 comprise four or other suitable number of horizontal rods 73 of varying lengths detachably plugged at one end 73a into apertures 74 in a cross bar 75 carried by two blocks 76, these blocks being hollowed or channelled as at 77 to fit a side member of the weaving frame so that the rods 73 project across the frame. When warping, the threads may be passed under and over the required rods and thereby leased and kept separated in a manner well known.

Additional uprights may be provided to support the weaving frame which normally rests at one end on the knee of the operator. These uprights can be adjusted at an angle to their normal vertical position relatively to the plates constituting the feet, and selected apertures at the upper ends of the uprights can have bolts or said rod passed through them and registering apertures in one end of the weaving frame.

The warper feature of this invention, as heretofore explained, may be embodied as a feature of the weaving apparatus, as illustrated in Fig. 10. After the warp has been wound the wing nuts 23 (see Fig. 3) may be unscrewed and the studs 22 removed from the aperture 5b or 5c, as the case may be, and inserted in the holes 5 adjacent the end of the bars 1, and the nuts 23 again screwed on the studs 22. With one end of the weaving frame so supported, the other end may rest on the weaver's lap.

A noticeable feature of this invention is the arrangement of the various frame parts which facilitates their disassembly and assembly whereby a complete set of weaving apparatus may be transported in a compact manner and erected at any desired site.

I claim:—

1. In a device for weaving, a support adapted to stand upon a floor, a weaving frame having side and end pieces, said frame being rotatably mounted upon said support and adapted to rotate upon said support in a substantially constant

plane through a complete circle under impulse of the hand, a comb carried in fixed position by said frame and arranged to revolve with said frame as the same is rotated, said comb having a multiplicity of warp thread receiving slots, said slots being open along one end, said warp being adapted to be laid lengthwise on and around said frame during rotation thereof and the warp threads being progressively inserted into individual slots with each complete revolution of said frame, said comb being movable on the frame after the warp threads are laid while retaining the warp threads in the slots to beat up the weft.

2. In a device as defined in claim 1, wherein the comb is composed of a multiplicity of teeth arranged in line, adjoining teeth forming said slots and a closure bar closing said slots after warping is completed.

3. In a device as defined in claim 1, including heddle bars normally extending transversely across and above the frame adjacent the middle thereof, the heddle rods being removable to permit the warp threads to be continuously laid lengthwise on said frame during rotation thereof and beneath the normal plane assumed by said heddle bars during weaving.

4. In a device for weaving, a support adapted to stand upon a floor and to be readily moved from place to place, a frame having side and end pieces, said frame being pivotally mounted upon said support, said pivot being arranged in a horizontal direction to permit said frame to be rotated end over end, a comb carried by said frame and arranged to slide lengthwise with respect to said frame, said comb having a multiplicity of teeth and an open top permitting insertion of warp threads between adjoining teeth of said comb, said frame being rotatable to lay the warp thereupon and permitting the individual warp threads to be inserted between said comb teeth, and positive means for releasably retaining said comb in a stationary position on the frame during warping, said comb being movably supported on said frame after the warp threads have been laid by the warp threads passing therethrough and being guided by said warp threads during reciprocation in the weaving operation, said frame being adjustable angularly with respect to said stand to position one end of said frame and comb at any desired height to accommodate the position of the weaver.

5. In a device as defined in claim 1, a heddle frame mounted on the side members of the weaving frame, heddle rods, notches in the heddle frame for receiving the heddle rods, the heddle rods being removable to permit the warp threads to be continuously laid lengthwise on said frame during rotation thereof and beneath the normal plane assumed by said heddle bars during weaving.

MARGARET L. THACKERAY.
